UNITED STATES PATENT OFFICE.

LEE S. CHADWICK, OF CLEVELAND, OHIO, ASSIGNOR TO THE CLEVELAND METAL PRODUCTS COMPANY, OF CLEVELAND, OHIO, A CORPORATION OF OHIO.

OIL BURNER.

Application filed April 29, 1920. Serial No. 377,466.

To all whom it may concern:

Be it known that I, LEE S. CHADWICK, a citizen of the United States, residing at Cleveland, in the county of Cuyahoga and State of Ohio, have invented a certain new and useful Improvement in Oil Burners, of which the following is a full, clear, and exact description, reference being had to the accompanying drawings.

This invention relates to improvements in oil burners, particularly of the class wherein tubular wicks are employed and wherein commingling tubes or suitable chimneys are used; and the aim is to combine with a wick stop, preferably of the gravity lock type, means both for clamping down the wick stop, and for elevating and maintaining elevated through the intervention of the wick stop the commingling tubes or chimney, in order to facilitate lighting. A further object is to construct said means so that by a natural and continuous lifting of an operating handle the parts are raised and locked in elevated position, and by a similar downward movement of the handle the parts are lowered and the wick stop locked against upward movement by the wick.

Simplicity of construction, convenience of production, and economy of manufacture are among the further objects of the invention.

In the drawings accompanying and forming a part hereof, Fig. 1 is a central vertical section through a burner embodying my invention and showing the parts in normal position; Fig. 2 is a similar view showing the commingling tubes lifted for the purpose of lighting the burner; Fig. 3 is a plan of the burner with the commingling tubes and wick stop removed; Fig. 4 shows the wick stop in side elevation; and Fig. 5 is an underneath perspective view of the lower end of the burner.

The burner is comprised of inner and outer wick tubes 1 and 2, respectively, connected at their lower ends as indicated at 3 with a liquid tight joint so as to enclose an annular wick space within which a wick 5, supported within a carrier 6, is adapted to be raised and lowered by the usual wick raising spindle 7 that is shown in dotted lines in Fig. 1 and which is provided with suitable star wheels or pinions 8, the teeth whereof are arranged to mesh with the perforations 9 in the carrier 6, all of which is well known to those acquainted with the

art and is therefore deemed unnecessary of a more detailed description and illustration. The outer end of the spindle 7 is equipped with a hand wheel 10.

Near their upper ends the respective wick tubes 1 and 2 are provided with ledges 11 and 12. Fixed within the inner wick tube with its periphery engaged beneath the ledge 11 is a perforated frustoconical plate 15 having a central guide aperture shown as surrounded by a flange 16. A cylindrical head 17 is guided within the aperture of the plate 15 and is supported through a link 18 from a lever 19 to which it is pivoted at 20, and the lever, in turn, is pivotally supported from a bracket 21 that extends inwardly from the rear portion of the inner wick tube 1. The link 18 passes upward through a bottom plate 22 of the head 17 and has its upward end connected to the central portion of a spider 23 (in the present instance by having tongues 24 that are projected through slots in the spider and turned over therebeyond). The central portion of the spider is connected, through arms 25, with a peripheral flange 26 that is secured to the cylindrical shell of the head near its upper end.

The wick stop, which is shown in detail in Fig. 4 and designated generally by the reference numeral 30, is made up of a member having a circular central portion 31, a perforated frustoconical portion 32 rising therefrom and surrounded by an annular depressed portion 33 that is skirted by an upwardly directed flange 34 from which stop fingers 35 project upwardly and then outwardly over the wick space between the tubes 1 and 2, when the annular depressed portion 33 is resting upon ledge 11. Secured to the underneath side of the circular central portion 31 of the wick stop, as by having fingers 36 which are projected through slots in the portion 31 and turned over therebeyond, is a shallow cylindrical portion of a member 37 that terminates at its lower end in a series of locking fingers 38, the respective front and rear edges 39 and 40 of each finger diverging upwardly from the rounded inwardly curved lower end of the finger, the front edge being cut in abruptly at a given elevation to form a notch 41 and create a locking lug 42. This general form of wick stop is shown and claimed in Patent No. 1,258,395 issued to my assignee on March 5, 1918.

Resting normally with their respective lower ends upon the flange 12 of the outer wick tube 2 and within the annular depressed position 33 of the wick stop; are the outer and inner commingling tubes 45 and 46, which are enclosed within a drum or chimney 47, and the inner of which has a diaphragm 48 set within its lower end. These commingling tubes, with the enclosing drum or chimney, are substantially the same as those shown in the patent above referred to, and are well known in the art.

The burner derives its supply of oil from a pipe 50 upon which the burner is mounted and to which it has communicative connection through the usual fitting 51. The previously mentioned lever 19 extends down over and in front of the pipe 50 and has pivotally connected to its lower end a latch plate 52 including an operating handle 53; and the latch plate is held in a plane parallel to that of the lever by a stop lug 54 that extends from the rear edge of the lever and is bent laterally and then forwardly over the outer side of the latch plate. The operating handle 53 projects through a slot 56 in a keeper plate 57 that is attached to the front portion of the inner wick tube adjacent its lower end, and curves downwardly and rearwardly therefrom. Extending laterally from one side of the slot 56 is a locking notch 58, and slightly below the plane thereof and from the other side of the slot extends a locking notch 59. The ends of the latch plate are turned laterally in opposite directions, as indicated at 60 and 61, to form locking lugs for cooperation with these respective notches 58 and 59 for a purpose presently to be explained; the lugs terminating at their inner ends in stops 62 and 63, respectively.

In order to obtain a clearer understanding as to the nature and mode of operation of the construction herein described, let it be assumed that the commingling tubes and drum (which constitutes a self contained unit) are removed from the burner, the wick stop 30 withdrawn; and the head 17 in the position shown in Fig. 1. To assemble the parts for use, the wick stop is lowered into the upper end of the inner wick tube and the locking fingers 38 projected between the arms 25 of the spider 23. As the wick stop settles into position, with its annular depressed portion 33 upon the ledge 11, the locking fingers automatically adjust themselves between the arms 25 of the spider, the final action being the cam-like engagement of the upper portions of the rear edges 40 of the fingers with the arms of the spider to project the locking lugs 42 beneath the arms adjacent thereto. When so interlocked with the spider in a bayonet joint like manner, the wick stop is held against upward movement independ-

ently of the head 17 so that as long as the head is restrained against upward movement, the wick stop cannot be elevated. The head is held against rising by reason of the fact that the locking lug 60 of the latch plate 52 is engaged within the notch 58 of the keeper plate 57. When the parts are in the position described, the commingling tubes may be placed in the position illustrated in Fig. 1. Now, when it is desired to light the burner, the operating handle 53 is lifted. The initial movement of the latch plates which is afforded by its pivotal connection with lever 19, withdraws the locking lug 60 from notch 58, and further movement results in the lever 19 being swung upwardly to lift, through the intervention of the link 18, head 17, wick stop 30, and the commingling tubes and drum. As the parts approach their elevated positions the locking lug 61 enters the notch 59 to hold the parts in the position illustrated in Fig. 2. There is no danger of accidental dislodgment of the parts from this position for the reason that the locking lug abuts squarely the side of the notch. To lower the parts, the foregoing operation is reversed, the initial downward movement of the operating handle serving to swing the latch plate on its pivot and withdraw the locking lug 61 from notch 59. The stops 62 and 63 prevent the locking lugs from passing entirely through their respective notches by engaging the rear side of the keeper plate.

Having thus described my invention, what I claim is:

1. In a burner of the character set forth, the combination of a supporting member movable vertically with respect to the wick, a wick stop carried thereby, the wick stop serving to support a flame enclosing element, and means for raising and lowering the aforesaid member.

2. In a burner of the character set forth, the combination of a supporting member movable vertically with respect to the wick, a wick stop carried thereby, said stop serving to support a flame enclosing element, and means for raising and lowering the aforesaid member and for locking it in low and elevated position.

3. In a burner of the character set forth, the combination of a supporting member movable vertically with respect to the wick, a wick stop carried thereby and being adapted to support a flame enclosing element, means for raising and lowering said member, a latch incorporated in said means, and a keeper plate fixed with respect to the burner and having parts wherewith parts of the latch cooperate to lock the aforesaid member in either low or elevated position.

4. In a burner of the character set forth, the combination of a supporting member

- movable vertically with respect to the wick, a wick stop carried thereby and adapted to support a flame enclosing element, means for raising and lowering the member, a latch plate pivotally connected to said means and having spaced locking parts that are disposed on opposite sides of its pivotal connection with said means, and a keeper plate along which the latch plate is movable and having abutments wherewith the respective locking parts of the latch plate are adapted to cooperate to hold the aforesaid member in either an elevated or low position.
5. In a burner of the character set forth, the combination of a supporting member movable vertically with respect to the wick, a wick stop carried thereby and adapted to support a flame enclosing element, means for raising and lowering the member, a latch plate pivotally connected to said means and having spaced locking parts disposed on opposite sides of its pivotal connection with said means, and a keeper plate fixed with respect to the burner, the keeper plate having abutment portions into operative relation with one of which one of the aforesaid locking parts of the latch plate is adapted to be moved through the swinging of the latch plate by gravity when the aforesaid member is in low position, and into holding engagement with the other of which the second locking part of the latch plate is adapted to be moved when the aforesaid member is lifted to elevated position.
35. 6. In a burner of the character set forth, the combination of a supporting member movable vertically with respect to the wick, a wick stop carried thereby and adapted to support a flame enclosing element, means for raising and lowering the member, a latch plate pivotally connected to said means and having spaced locking parts disposed on opposite sides of its pivotal connection with said means and incorporating an operating handle, and a keeper plate fixed with respect to the burner and along which the latch plate is movable, the keeper plate having abutment portions into operative relation with one of which one of the aforesaid locking parts of the latch plate is adapted to be moved through the latch plate being swung by gravity of the handle when the aforesaid member is in low position, and into holding engagement with the other of which the second locking part of the latch plate is adapted to be moved when the latch plate is lifted by said handle to move the aforesaid member to elevated position, the keeper plate constituting a guide for the latch plate during the latter's movement.
55. 7. In a burner of the class set forth, the combination of inner and outer wick tubes, a supporting member movable vertically within the inner wick tube, a wick stop having interlocking engagement with said mem-
- ber and including fingers projecting outwardly over the space between the wick tubes, and means for raising and lowering the aforesaid member and for holding it in either elevated or low position, the wick stop serving to support a flame enclosing element.
8. In a burner of the class set forth, the combination of inner and outer wick tubes, an annulus fixed within the inner wick tube, a cylindrical head guided for vertical movement within the annulus, a spider supported by said head, a wick stop having interlocking engagement with the spider and arranged to support a frame enclosing element, means for raising and lowering the head, a latch plate pivotally connected to said means and having locking lugs situated on opposite sides of its pivotal connection with said means, said latch plate having an operating handle, and a keeper plate fixed with respect to the wick tube and depending therefrom, the keeper plate having a slot through which the handle of the latch plate projects and being provided with notches extending from the slot and into which the locking lugs of the latch plate are adapted to be projected for holding the aforesaid head in either an elevated or low position.
9. In a burner of the class set forth, the combination of inner and outer wick tubes, an annulus fixed within the inner wick tube, a cylindrical head guided for vertical movement within the annulus, a spider supported by said head, a wick stop having interlocking engagement with the spider and arranged to support a flame enclosing element, means for raising and lowering the head, a latch plate pivotally connected to said means and having locking lugs situated on opposite sides of its pivotal connection with said means, said latch plate having an operating handle, and a keeper plate fixed with respect to the wick tube and depending therefrom, the keeper plate having a slot through which the handle of the latch plate projects and being provided with notches extending from the slot and into which the locking lugs of the latch plate are adapted to be projected for holding the aforesaid head in either an elevated or low position, the latch plate having stops for engagement with the keeper plate to prevent the locking lugs from passing too far through the notches.
10. In a burner of the class set forth, the combination of inner and outer wick tubes, a guide supported within the inner wick tube, a head movable vertically within said guide, a member adapted to be placed upon said head and automatically lock itself thereto against relative vertical movement, the member including a stop part projecting over the space between the tubes and being

adapted to support a flame enclosing element, and means for raising and lowering the head and for locking it in either an elevated or low position.

5 11. In a burner of the character set forth, in combination with the wick, a head supported in operative relation to the wick for vertical movement with respect thereto, a flame enclosing element and a wick stop 10 that are sustained by and movable with said head; and means for raising and lowering said head and for locking it in low position and in elevated position whereby the wick stop may be restrained against elevation and 15 the flame enclosing element may be held raised while the parts are in the respective positions aforesaid.

12. In a burner of the character set forth, in combination with the wick, a head supported in operative relation to the wick for vertical movement with respect thereto, a device carried by said head and adapted to support a flame enclosing element, means for raising and lowering the head, a latch plate 20 pivotally connected to said means, said latch plate having locking parts, and a keeper plate along which the latch plate is movable and having abutments wherewith the respective locking parts of the latch plate are 25 adapted to cooperate to hold the aforesaid member in either an elevated or low position.

30

13. In a burner of the class described, the combination of inner and outer wick tubes, a supporting member guided for vertical movement within the inner wick tube, a device interlocking with the member and adapted to support a flame enclosing element, a lever pivotally supported adjacent the lower end of the inner wick tube, a link 40 connecting the lever and member, a keeper plate supported in fixed relation to the wick tubes and along which the end of the lever is arranged to swing, and a latch plate pivoted to the lever and having locking parts, the keeper plate having abutment portions wherewith the locking parts of the latch plate are designed to engage to lock the aforesaid member in either an elevated or 45 low position.

50 14. In a burner of the class set forth, the combination of a vertically movable member adapted to support a flame enclosing element, a pivotally supported lever wherewith said member has connection, a keeper, and a latch pivotally connected to the lever and having locking parts for engagement with parts of the keeper to lock the aforesaid member in either an elevated or low position.

55 60 In testimony whereof, I hereunto affix my signature.

LEE S. CHADWICK.
